ELECTRIC OUTBOARD MACHINE

This application is based on and claims the benefit of priority from Japanese Patent Application No. 2022-051497, filed on 28 Mar. 2022, the content of which is incorporated herein by reference.

BACKGROUND OF THE INVENTION

Field of the Invention

The present invention relates to an outboard machine attached to a rear part of a boat.

Related Art

A general outboard machine includes an engine that uses gasoline as fuel.

Patent Document 1: Japanese Unexamined Patent Application, Publication No. 2021-146932

SUMMARY OF THE INVENTION

Nowadays, however, it has been required to use an electric motor in place of the engine for reduced carbon dioxide emission and low adverse environmental impact. The inventors of the present disclosure have focused on the fact that an electric outboard machine, which is an outboard machine including an electric motor, has room for improvement in impact resistance.

Under these circumstances, the present invention has been achieved to improve the impact resistance of the electric outboard machine.

The inventors have found that the impact resistance of the electric outboard machine improves when a motor of an outboard machine body and an attachment for attaching the outboard machine body to the boat are arranged to sandwich a controller that controls the motor, and have achieved the present invention. The present invention is directed to an electric outboard machine of aspects (1) to (9).

(1) An electric outboard machine, including: an outboard machine body including a propeller, an electric motor that drives the propeller, and a controller that controls the motor; and an attachment for attaching the outboard machine body to a rear part of a boat, wherein the controller is located between the motor and the attachment.

In this aspect, if another boat collides with the boat from behind, the controller arranged between the motor and the attachment is easily protected from the impact of the rear-end collision. This can improve impact resistance of the electric outboard machine.

(2) The electric outboard machine of Aspect (1), wherein the boat is equipped with a battery, a DC cable that supplies power from the battery to the controller is routed, and the power is supplied from the controller to the motor.

In this aspect, it is required to electrically connect the battery of the boat and the controller with the DC cable, and electrically connect the controller and the motor. In this point, the controller located between the boat and the motor can efficiently shorten the DC cable. Compared with when the controller is arranged behind the motor, i.e., when the controller and the battery are arranged to sandwich the motor, no space is required for routing the DC cable above or on the side of the motor. This leads to downsizing of the outboard machine body.

(3) The electric outboard machine of aspect (1) or (2), wherein the controller includes a control circuit that controls

2

the motor and a controller case that houses the control circuit, and the attachment is wider than the controller case in a lateral direction of the boat, and an edge of the attachment in the lateral direction of the boat is located outward of an edge of the controller case in the lateral direction of the boat.

In this aspect, the controller is easily protected from impact applied in the lateral direction of the boat.

(4) The electric outboard machine of any one of aspects (1) to (3), wherein the outboard machine body includes a housing that houses the motor, and the housing is wider than the controller in a lateral direction of the boat, and an edge of the housing in the lateral direction of the boat is located outward of an edge of the controller in the lateral direction of the boat.

In this aspect, the controller is easily protected from impact applied in the lateral direction of the boat.

(5) The electric outboard machine of any one of aspects (1) to (4), wherein a gap is provided between a front surface of the controller and the attachment in a case where no external force is applied to the electric outboard machine in a front-rear direction of the boat.

In this aspect, although impact is applied to the boat from behind, the controller is not crushed between the motor and the attachment unless the gap is lost.

(6) The electric outboard machine of aspect (5), wherein a stopper is provided to one selected from the outboard machine body and the attachment, and, in a case where a forward external force is applied to the electric outboard machine, the stopper contacts the other one selected from the outboard machine body and the attachment before loss of the gap to prevent loss of the gap.

In this aspect, although a forward external force is applied to the electric outboard machine upon rear-end collision, the stopper prevents loss of the gap between the front surface of the controller and the attachment.

(7) The electric outboard machine of aspect (6), wherein the attachment supports the outboard machine body via a damper that absorbs impact in the front-rear direction, and a regulating part that regulates a stroke for the damper to absorb the impact serves as the stopper.

This configuration can avoid adverse effects, such as crushing of the controller when forward impact is excessively absorbed by the damper.

(8) The electric outboard machine of aspect (6) or (7), wherein the outboard machine body includes a protrusion that protrudes forward beyond a front surface of the controller, and the protrusion serves as the stopper.

In this aspect, the stopper can be obtained by providing the outboard machine body with the protrusion that protrudes forward.

(9) The electric outboard machine of any one of aspects (1) to (8), further including: a drive shaft that transmits power of the motor to the propeller, wherein the outboard machine body includes an upper unit including the controller and the motor and a lower unit including the propeller, and in a case of turning to change a traveling direction of the boat, the lower unit rotates about an axis of the drive shaft relative to the upper unit.

In this aspect, when turning the boat, the lower unit rotates relative to the upper unit including the controller and the motor. Thus, the controller and the motor do not rotate, and the cable that supplies the power to the controller and the motor does not rotate. This can reduce damage to the cable. Moreover, there is no need to save space for the cable to

bend during the turn, or to make the cable long enough to be able to bend. This leads to downsizing of the outboard machine body.

Aspect (1) can improve the impact resistance of the electric outboard machine. Aspects (2) to (9) referring to aspect (1) provide additional advantages.

BRIEF DESCRIPTION OF THE DRAWINGS

FIG. 1 is a side view illustrating an electric outboard machine of a first embodiment;

FIG. 2 is a perspective view illustrating the electric outboard machine;

FIG. 3 is a plan view illustrating a connection between an attachment and an outboard machine body;

FIG. 4 is a sectional side view illustrating the connection between the attachment and the outboard machine body;

FIG. 5 is a sectional side view illustrating a variation of an example shown in FIG. 4;

FIG. 6 is a sectional side view illustrating a tilt device of the attachment; and

FIG. 7 is an exploded plan view illustrating a controller and a motor.

DETAILED DESCRIPTION OF THE INVENTION

Embodiments of the present invention will be described below with reference to the drawings. Note that the present invention is not limited to the following embodiment, and modifications can be made as appropriate without departing from the scope of the invention.

FIG. 1 is a side view illustrating an electric outboard machine 70 of a first embodiment. The electric outboard machine 70 is attached to a rear part of a boat 10. Hereinafter, the front side of the boat 10 will be referred to as the "front Fr", the rear side of the boat 10 as the "rear Rr", the left side of the boat facing the front Fr as the "left L", and the right side of the boat facing the front Fr as the "right R". The "left" and "right" of the boat mentioned below may be recognized as the lateral sides of the boat, and the "left-right direction" may be recognized as a "lateral direction" of the boat.

The electric outboard machine 70 includes an outboard machine body 60 and an attachment 50. The attachment 50 attaches the outboard machine body 60 to the rear part of the boat 10. The boat 10 is equipped with a battery 15. A DC cable 16 is routed between the boat 10 and the outboard machine body 60 to supply the power of the battery 15 to the outboard machine body 60.

The attachment 50 includes a fixing part 51, a swivel 57, and a tilt device 54. The fixing part 51 is, for example, a clamping mechanism, and is fixed to an upper part of a transom 19 in the rear part of the boat 10. An upper end of the swivel 57 is rotatably attached to an upper end of the fixing part 51 via a tilt shaft 56 extending in the left-right direction L-R. The swivel 57 supports a front end of the outboard machine body 60. The tilt device 54 allows the swivel 57 to rotate about the tilt shaft 56 relative to the fixing part 51 to tilt the outboard machine body 60. The tilt device 54 will be described in detail later.

The outboard machine body 60 includes a controller 61, a motor 62, a reduction gear 63, a drive shaft 64, a bevel gear 65, a propeller 66, a housing 67, and a cover 68. The housing 67 houses the controller 61, the motor 62, and the reduction gear 63. The cover 68 covers the housing 67 from outside.

The controller 61 is a device for controlling the motor 62, and is arranged in front of the motor 62. Thus, the controller 61 is arranged between the motor 62 and the attachment 50. The controller 61 includes a controller case 61a, a control circuit 61b, an inverter 61c, and a controller connector 61d. The controller case 61a houses the control circuit 61b and the inverter 61c. The control circuit 61b and the inverter 61c are electrically connected to the battery 15 via the DC cable 16. The inverter 61c converts DC power supplied from the battery 15 to AC power. The controller connector 61d is an output terminal from which the converted AC power is outputted, and is arranged on a rear surface of the controller case 61a. The control circuit 61b controls the inverter 61c based on a command from a pilothouse on the boat 10 to control the motor 62.

The motor 62 is an electric motor, more specifically, an AC motor operated by the AC power. The motor 62 includes a motor case 62a, a motor connector 62b, a stator 62c, a rotor 62d, and a motor shaft 62e. The motor connector 62b is an input terminal from which the AC power is inputted, and is arranged on a front surface of the motor case 62a. The controller connector 61d and the motor connector 62b engage with each other to electrically connect the inverter 61c and the motor 62.

The motor shaft 62e extends in a vertical direction. The rotor 62d is fixed to the motor shaft 62e and rotates together with the motor shaft 62e. The stator 62c allows the rotor 62d to rotate by the AC power supplied from the inverter 61c to cause the motor shaft 62e to rotate.

The drive shaft 64 extends in the vertical direction. An upper end of the drive shaft 64 meshes with a lower end of the motor shaft 62e via the reduction gear 63.

The propeller 66 includes a propeller shaft 66a extending in the front-rear direction Fr-Rr and a propeller body 66b that is fixed to the propeller shaft 66a and rotates together with the propeller shaft 66a. A front end of the propeller shaft 66a meshes with a lower end of the drive shaft 64 via the bevel gear 65. The bevel gear 65 may simply change the direction of rotation of the shaft, or may change the direction of rotation and reduce the rotation speed of the shaft.

The above-described configuration allows the motor 62 to drive the propeller 66. An upper unit 60a, which is an upper part of the outboard machine body 60, includes the controller 61, the motor 62, the reduction gear 63, the housing 67, and the cover 68. A lower unit 60b, which is a lower part of the outboard machine body 60, includes the bevel gear 65 and the propeller 66. The lower unit 60b is attached to be rotatable about an axis of the drive shaft 64 relative to the upper unit 60a.

The upper unit 60a has a rotation device 60c in the housing 67. The rotation device 60c allows the lower unit 60b to rotate about the axis of the drive shaft 64 relative to the upper unit 60a based on a command from the pilothouse 12 to change the propelling direction of the propeller 66 so that the traveling direction of the boat 10 changes. Specifically, the rotation device 60c includes, for example, another motor (not shown) different from the motor 62, and transmits the rotatory power of the motor to the lower unit 60b via, for example, a worm gear set, so that the lower unit 60b rotates about the axis of the drive shaft 64.

FIG. 2 is a perspective view illustrating the electric outboard machine 70 as observed from the front right side. The swivel 57 includes two upper arms 57a and two lower arms 57b. The two upper arms 57a support a front upper end part of the housing 67 at two points spaced from each other in the left-right direction. The two lower arms 57b support a front lower end part of the housing 67 at two points spaced

from each other in the left-right direction. Specifically, the two upper arms **57a** support the front upper end part of the housing **67** above the top end of the controller **61**. The two lower arms **57b** support the front lower end part of the housing **67** below the bottom end of the controller **61**.

FIG. 3 is a plan view illustrating a connection between the attachment **50** and the outboard machine body **60** as observed from above. The upper arms **57a** respectively extend straight to the rear side. The lower arms **57b** respectively extend outward to the left side and the right side, and then extend to the rear side. Thus, a gap between the two lower arms **57b** in the left-right direction is larger than a gap between the two upper arms **57a** in the left-right direction. The attachment **50** thus has, as a width in the left-right direction, a dimension from the left end of the lower arm **57b** on the left L to the right end of the lower arm **57b** on the right R.

The controller case **61a** has, as a width in the left-right direction, a dimension between the left and right end faces of the controller case **61a**. The housing **67** has, as a width in the left-right direction, a dimension between the left and right end faces of the housing **67**.

Each of the attachment **50** and the housing **67** has a larger width in the left-right direction L-R than the controller case **61a**. Thus, each of the attachment **50** and the housing **67** has left and right edges located outward of left and right edges of the controller case **61a**. That is, each of the swivel **57** and the housing **67** has the left edge on the left L of the left edge of the controller case **61a** and the right edge on the right R of the right edge of the controller case **61a**.

A gap **G** is provided in the front-rear direction between a front surface of the controller **61** and the swivel **57** when no external force is applied to the outboard machine body **60** in the front-rear direction. The gap **G** will be referred to as a “protective gap **G**”. The protective gap **G** protects the controller **61** from a forward external force applied to the outboard machine body **60** upon rear-end collision. Each of the upper arms **57a** and the lower arms **57b** supports the front end part of the housing **67** via a damper **58**.

FIG. 4 is a sectional side view of the damper **58** of the upper arm **57a** as observed from the right R. The damper **58** has an insertion member **58c**, an elastic member **58d**, a front regulating part **58a**, and a rear regulating part **58b**. The insertion member **58c** is a shaft member that extends in the front-rear direction Fr-Rr and is attached to the rear end of the upper arm **57a** to protrude to the rear side Rr from the rear end of the upper arm **57a**. The insertion member **58c** is inserted in an insertion hole **67h** that penetrates the housing **67** in the front-rear direction Fr-Rr. The elastic member **58d** is, for example, a rubber member, and is joined to an outer peripheral surface of the insertion member **58c** and an inner peripheral surface of the insertion hole **67h**.

The front regulating part **58a** is arranged on the insertion member **58c** on the front side Fr of the insertion hole **67h** to regulate a forward stroke for the damper **58** to absorb impact. The rear regulating part **58b** is arranged on the insertion member **58c** on the rear side Rr of the insertion hole **67h** to regulate a rearward stroke for the damper **58** to absorb impact.

Upon a forward external force being applied to the outboard machine body **60**, the rear surface of the front regulating part **58a** comes into contact with the front surface of the housing **67** before loss of the protective gap **G**. Thus, the front regulating part **58a** also functions as a stopper that prevents loss of the protective gap **G**. Thus, when no external force is applied to the outboard machine body **60** in the front-rear direction, a gap **g** provided in the front-rear

direction between the front surface of the housing **67** and the front regulating part **58a** is smaller than the protective gap **G**.

The controller **61** includes a front cover **61e** that covers the controller case **61a** from the front Fr, and a gap between a front surface of the front cover **61e** and the attachment **50** serves as the protective gap **G**.

The damper **58** of the lower arm **57b** is configured in the same manner as the damper **58** of the upper arm **57a** described above.

FIG. 5 is a view illustrating a variation of FIG. 4. The outboard machine body **60** may further include a protrusion **59** that protrudes forward Fr beyond the front surface of the controller **61**. The protrusion **59** serves as a stopper that prevents loss of the protective gap **G** in place of or together with the front regulating part **58a**. Specifically, upon a forward external force being applied to the outboard machine body **60**, a front end of the protrusion **59** comes into contact with the attachment **50** before loss of the protective gap **G**. Thus, when no external force is applied to the outboard machine body **60** in the front-rear direction, a gap **g2** provided in the front-rear direction between the front end of the protrusion **59** and the attachment **50** is smaller than the protective gap **G**.

FIG. 6 is a sectional side view illustrating a tilt device **54**. The tilt device **54** includes an actuator **54a**. The actuator **54a** allows the swivel **57** to rotate relative to the fixing part **51** to tilt the outboard machine body **60** based on a command from a pilothouse on the boat **10**. The actuator **54a** may be, for example, a cylinder such as a hydraulic cylinder as shown in FIG. 6, or may be another motor different from the motor **62**.

FIG. 7 is an exploded plan view illustrating the controller **61** and the motor **62**. As described above, the controller connector **61d** in the controller case **61a** and the motor connector **62b** in the motor case **62a** engage with each other to electrically connect the controller **61** and the motor **62**.

The configuration and advantages of the present embodiment will be summarized below.

The controller **61** is located between the motor **62** and the attachment **50**. Thus, if another boat collides with the boat **10** from behind, the controller **61** is easily protected from the impact of the rear-end collision. This can improve impact resistance of the electric outboard machine **70**.

The battery **15** in the boat **10** supplies the DC power to the controller **61** via the DC cable **16**, and the controller **61** converts the DC power to the AC power to supply the AC power to the motor **62**. In this point, the controller **61** located between the boat **10** and the motor **62** can efficiently shorten the DC cable **16**. Compared with when the controller **61** is arranged on the rear side Rr of the motor **62**, i.e., when the controller **61** and the battery **15** are arranged to sandwich the motor **62**, no space is required for routing the DC cable **16** above or on the side of the motor **62**. This leads to down-sizing of the outboard machine body.

Each of the attachment **50** and the housing **67** has a larger width in the left-right direction L-R than the controller case **61a**, and has a left and right edge located outward of a left and right edge of the controller case **61a** in the left and right direction. This configuration can easily protect the controller **61** from impact applied in the left-right direction L-R.

The protective gap **G** is provided between the front surface of the controller **61** and the attachment **50**. Thus, although a forward external force is applied to the outboard machine body **60** upon rear-end collision, the controller **61** is not crushed between the motor **62** and the attachment **50** unless the protective gap **G** is lost.

Due to application of the forward external force, the front surface of the housing **67** comes into contact with the front regulating part **58a** on the front side Fr of the damper **58** before loss of the protective gap G. This can avoid adverse effects, such as crushing of the controller **61** due to loss of the protective gap G when forward impact is excessively absorbed by the damper **58**.

When the outboard machine body **60** includes the protrusion **59** that protrudes forward Fr beyond the front surface of the controller **61** as described in the above variation, the front end of the protrusion **59** comes into contact with the attachment **50** before loss of the protective gap G, preventing loss of the protective gap G.

When turning the boat, the lower unit **60b** rotates relative to the upper unit **60a** including the controller **61** and the motor **62**. Thus, the controller **61** and the motor **62** do not rotate, and the DC cable **16** that supplies the power to the controller **61** and the motor **62** does not rotate. This can reduce damage to the DC cable **16**. Moreover, there is no need to save space for the DC cable **16** to bend during the turn, or to make the DC cable **16** longer to be able to bend. This leads to downsizing of the outboard machine body **60**.

OTHER EMBODIMENTS

The embodiments described above may be modified as follows, for example. The motor **62** may be a DC motor and the controller **61** may have no inverter **61c**. The dampers **58** may be omitted so that the arms **57a** and **57b** of the swivel **57** may directly support the housing **67** without the dampers **58**.

EXPLANATION OF REFERENCE NUMERALS

- 10** Boat
  - 15** Battery
  - 16** DC Cable
  - 50** Attachment
  - 58** Damper
  - 58a** Front regulating part as stopper
  - 59** Protrusion as stopper
  - 60** Outboard machine body
  - 61** Controller
  - 62** Motor
  - 66** Propeller
  - 67** Housing
  - 68** Cover
  - 70** Electric outboard machine
  - G** Protective gap as a gap provided in a front-rear direction between a front surface of the controller and the attachment
- What is claimed is:
- 1.** An electric outboard machine, comprising:
an outboard machine body including a propeller, an electric motor that drives the propeller, and a controller that controls the motor; and
an attachment for attaching the outboard machine body to a rear part of a boat,

wherein the controller is located between the motor and the attachment.

2. The electric outboard machine of claim **1**, wherein the boat is equipped with a battery,

a DC cable that supplies power from the battery to the controller is routed, and

the power is supplied from the controller to the motor.

3. The electric outboard machine of claim **1**, wherein the controller includes a control circuit that controls the motor and a controller case that houses the control circuit, and

the attachment is wider than the controller case in a lateral direction of the boat, and an edge of the attachment in the lateral direction of the boat is located outward of an edge of the controller case in the lateral direction of the boat.

4. The electric outboard machine of claim **1**, wherein the outboard machine body includes a housing that houses the motor, and

the housing is wider than the controller in a lateral direction of the boat, and an edge of the housing in the lateral direction of the boat is located outward of an edge of the controller in the lateral direction of the boat.

5. The electric outboard machine of claim **1**, wherein a gap is provided between a front surface of the controller and the attachment in a case where no external force is applied to the electric outboard machine in a front-rear direction of the boat.

6. The electric outboard machine of claim **5**, wherein a stopper is provided to one selected from the outboard machine body and the attachment, and, in a case where a forward external force is applied to the electric outboard machine, the stopper contacts the other one selected from the outboard machine body and the attachment before loss of the gap to prevent loss of the gap.

7. The electric outboard machine of claim **6**, wherein the attachment supports the outboard machine body via a damper that absorbs impact in the front-rear direction, and a regulating part that regulates a stroke for the damper to absorb the impact serves as the stopper.

8. The electric outboard machine of claim **6**, wherein the outboard machine body includes a protrusion that protrudes forward beyond a front surface of the controller, and the protrusion serves as the stopper.

9. The electric outboard machine of claim **1**, further comprising: a drive shaft that transmits power of the motor to the propeller, wherein

the outboard machine body includes an upper unit including the controller and the motor and a lower unit including the propeller, and

in a case of turning to change a traveling direction of the boat, the lower unit rotates about an axis of the drive shaft relative to the upper unit.
